Winterthur, SwitzerlandApplication July 16, 1931, Serial No. 551,256
In Germany July 30, 1930

4 Claims. (Cl. 19—70)

This invention relates to regulating devices in combined opening or scutching machines for cotton or similar fibres, wherein two or more eveners are combined together in order to produce laps 5 of very regular weight.

With a view to obtain with the aid of combined cotton opening machines bats of as nearly an accurate total weight as possible and a good uniformity from yard to yard, each of the sections 10 combined to an opening or scutching unit is provided with a separate feed regulating device. In order to produce the desired effect these devices must work in dependency on each other. For this purpose the well known feed regulating devices, commonly employed in cotton mills, consisting of evener rollers and series of levers connected to the belt shipper of a cone pulley regulator, could be interconnected in such manner that for example the driven cone pulley of one 15 evener drives by means of a belt, a rope or a chain and a shaft on the driving cone pulley of the next following evener. However, with such an arrangement the belt of the first pair of cone pulleys is compelled to actuate all the other eveners and the sections connected with them, thus being unduly strained. Consequently the accuracy of regulating is diminished, the belt beginning to slip on the cone pulleys and eventually resisting completely to being laterally displaced 20 thereon, so that the evenness of the laps results to be even worse than with each feed regulating device operating independently of the others.

According to the invention one of the driven cone pulleys cooperates with a differential drive 25 which transmits the rotational movement of said cone pulley to the evener of the preceding machine in supplementary manner.

Thus the driving belt of the first pair of cone pulleys is relieved, having to transmit not more 30 energy as is the case when the regulating devices are independently arranged, in that the differential drive actuates the next succeeding pair of pulleys and the driving belt so to speak only transmits the surplus energy required for regulating the first drive. Therefore the driving belt 35 is readily displaceable and no part of the draw is lost by slippage.

In the accompanying drawing a constructional 40 form of the invention is illustrated, by way of example only, in which

Fig. 1 shows in a vertical section a first constructional form of the invention including two feed regulating devices in driving association,

Fig. 2 on a smaller scale, in an elevation the

manner in which the feed regulating device is assembled with a set of machines.

Fig. 3 is a view similar to Fig. 1 of a second constructional form of the invention, and

Fig. 4 a view similar to Fig. 2 of this second form.

With the first constructional form the shaft of the calender head or lap head indicated in Fig. 2 drives by means of the spur gears 2 and 3 (Fig. 1) the lower cone pulley 4 of the feed regulating device 5 of the first machine. The shaft 6 of the lower cone pulley 4 imparts its motion by way of the chain wheel 7 and chain 8 to the chain wheel 9 which is secured to a hub of a casing 10. Within the latter two spur gears 11 and 12 rigidly connected to each other are accommodated and mounted on a shaft 13. The gear wheel 12 meshes with the gear 14 fixed on a shaft 15 which carries at its one end a worm 16 for driving the feed device. On the shaft 15 the upper cone pulley 17 is rotatably mounted which is firmly connected to a spur gear 18 which engages in a wheel 11. A chain 20 is passed over a chain wheel 19, secured to the other end of the shaft 15, and from there to chain wheel 21 rigid with a shaft 22, which transmits its rotational movement to the spur gears 23 and 24 of the second feed regulating device 25 for driving the cone pulleys 26 and 27 comprised by the same, said pulleys being operatively connected by the belt 28.

This feed regulating device operates as follows: From the shaft 6 of the lower cone pulley 4 of the feed regulating device 5 the casing 10 is driven by means of the chain drive 7, 8, 9 thus causing the spur gears 11 and 12 to perform an orbital movement about the shaft 15 of the upper cone pulley 17. Thereby the wheel 12 rolls on the wheel 14 to the extent which the gear 11 firmly connected to it and meshing with the wheel 18 permits. The wheel 18 is driven by the upper cone pulley 17 which in turn takes its drive from the lower cone pulley 4 by way of the belt 29. From this lower cone pulley 4 the wheel 18 is turned according to the position into which the driving belt 29 is adjusted in dependency on the position of the feed roller and by the aid of the casing 10 the shaft 15 is also turned at higher or lower speed. The shaft 15 transmits the movement imparted to it by means of the worm 16 to the feed roller of the respective machine and also by way of the chain drive 19, 20, 21 to the shaft 22 and thus to the cone pulleys 26 and 27 of the feed regulating device 25. The rotational movement of the shaft 1 is therefore transmitted

to the cone pulleys 26 and 27 of the feed regulating device 25 via the cone pulleys 4 and 17 of the speed regulating device 5 and the chains 8 and 20 through the intermediary of the differential drive 18, 11, 12, 14 housed in the casing 10. At the same time the upper cone pulley 17 of the feed regulating device 5 influences through the medium of the differential drive 18, 11, 12, 14 the whole drive in accordance with the ratio 10 of gearing between the cone pulleys 4 and 17 which is controlled by the respective position of the belt 29 on these pulleys.

With the second constructional form, from the calender head of the machine-set indicated in Fig. 4, again the lower cone pulley 4 of the feed regulating device 5 of the first section is driven by means of the shaft 1 via the gears 2 and 3. The shaft 6 of the lower cone pulley 4 may transmit its rotation to the lower cone pulley 26 of the pair of cone pulleys 26, 27 of the feed regulating device 25 by direct connection with shaft 6, however, the arrangement may be such that the shaft 6' is driven independently of the cone pulley 4, for example, by means of the wheels 41, 42 which in turn are actuated by the next following machine. The cone pulley 4 drives the cone pulley 17 by the aid of the belt 29 and thus the feed rollers of the first machine. The driven cone pulley 27 of the regulating device 25 is firmly connected to the casing 10 of the differential drive of which the wheel 12 which is rigid with the wheel 11 meshes with the wheel 14 keyed to the shaft 15. The wheel 11 engages in the wheel 18, the elongated hub of which carries at its end 35 the worm 29 for engagement with the wheel 30 for the feed roller.

This feed regulating device works as follows: The shaft 1 drives the lower cone pulley 4. The shaft 6 transmits this motion to the cone pulley 26 through shaft 6' unless the latter is driven directly by the bevel gear wheels 41, 42. The lower cone pulley 26 drives the upper cone pulley 27 and consequently the casing of the differential drive by means of the belt 28. Said casing imparts orbital movement to the wheels 12 and 11 which due to being carried on the shaft 13 perform at the same time a partial rolling movement on the wheels 14 and 18. The lower cone pulley 4 drives the cone pulley 17 of the first machine. Thereby the shaft 15 is set in motion and the wheel 14 fixed thereto together with it. The orbital movement of the wheels 12 and 11 and the rotation of the wheel 14 result in a combined movement of the wheel 18 which is then transmitted to the worm 29 and thus to the worm wheel 30 of the drive for the feed roller.

With this arrangement primarily each belt of the cone pulley drives transmits to the driven cone pulley only so much energy as is required for actuating the feed regulating device. The belt of the first pair of cone pulleys transmits in addition the energy consumed by the differential drive which, however, is only a fraction of the energy

required for driving the feed rollers so that the belt is by no means unduly strained. Consequently all the belts are readily displaceable with ease.

This feed regulating device can be used for any type of cone pulley speed regulators, i. e. for eveners with sectional plates above or for regulators with piano levers below the evener rollers.

I claim,

1. In a feed regulating device for openers and lappers for cotton or other fibrous material, consisting of at least two beater sections, a cone pulley evener for each beater section, a driving pulley and a driven pulley for each cone evener, a differential drive, means for operatively connecting said differential drive with one of said driven pulleys and adapting said differential drive to transmit the movement of said driven pulley to the cone pulley drive of the preceding section in supplementary manner so as to relieve the belt thereof, and to regulate the speed of one of said cone pulley eveners in accordance with the speed of another of said cone pulley eveners and actuating means for said differential drive. 20

2. In a feed regulating device for openers and lappers for cotton or other fibrous material, consisting of at least two beater sections, a cone pulley evener for each beater section, a driving pulley and a driven pulley for each cone evener, feed regulating means for each section, a differential drive actuated by the driving pulley of the succeeding section, means for operatively connecting said differential drive with the driven pulley of said succeeding section, and transmission means for imparting the drive to the driving pulley of the feed regulating means of the preceding section. 35

3. In a feed regulating device for openers and lappers for cotton and other fibrous material having a plurality of beater sections, the combination of a feeding means for each of said beater sections, a variable speed cone pulley belt drive for each feeding means, a differential drive interposed between said belt drives, adapted to regulate the speed of one of said feeding means in accordance with the speed of another of said feeding means and to substantially equalize the loads on the belts of said belt drives. 45

4. In a feed regulating device for beater sections of opener and lapper machines for cotton or other fibrous material, comprising a plurality of pairs of cone pulleys, independent driving means for each of said pairs, each of said pairs comprising a driving cone and a driven cone, a differential drive, the driven pulley of one of said pairs of cone pulleys being connected with said differential drive, the driven cone of said other pair of cone pulleys driving the differential drive, said differential drive and the driven cone of said second cone pair driving the feed of one of said beater sections, the first of said cone pairs driving the feed drive of another of said beater sections. 50 55 60
